UNITED STATES PATENT OFFICE.

CLARA ALLING KIBBE, OF TERLTON, OKLAHOMA.

CHURN STAND.

1,402,620.

Specification of Letters Patent.

Patented Jan. 3, 1922.

Application filed August 23, 1921. Serial No. 494,518.

To all whom it may concern:

Be it known that I, CLARA A. KIBBE, a citizen of the United States, and a resident of Terlton, in the county of Pawnee and State of Oklahoma, have invented a new and Improved Churn Stand, of which the following is a full, clear, and exact description.

This invention relates to improvements in churn stands, and more particularly to a stand which is adapted to hold a churn or other receptacle or device, and while I shall hereinafter refer to the same as a churn stand, it is to be understood that the invention is not limited to any particular use as it is capable of a wide range of utility in supporting receptacles of all sorts.

An object of the invention is to provide a stand of the character stated, which may be clamped to a table or other support and it is provided with hinged walls capable of forming a receptacle when in vertical position and adapted to be folded flat upon the base supporting the same and occupy but a minimum of space for storage or shipment.

A further object is to provide a stand of the character stated which can be manufactured and sold at an extremely low price, which will be strong and durable in use and which will most efficiently perform the functions for which it is intended.

With these and other objects in view the invention consists in certain novel features of construction, and combination and arrangements of parts as will be more fully hereinafter described and pointed out in the claims.

In the accompanying drawings—

Figure 1 is a view in vertical section taken on the line 1—1 of Figure 2 illustrating my improved churn stand in position on a table.

Figure 2 is a top plan view of the stand in operative position on a table.

Figure 3 is a perspective view of the stand in its folded or knocked-down form.

My improved churn stand comprises a base 1 and four walls 2, 3, 4 and 5 respectively which are secured to the base 1 by hinges 6. The base 1 and the walls 2, 3, 4 and 5 are preferably of wood, although they may be of any suitable material and proportion as may be desired in accordance with the functions to be performed.

For clearness of description I shall hereinafter refer to the walls 2 and 5 as side

walls and the walls 3 and 4 as end walls, although, as illustrated, it is preferable that these walls shall be of the same or approximately the same length to form a square 60 receptacle when the walls are in upright position, although it is to be understood that the invention is not limited to the particular shape of the receptacle as it is obvious that this shape may be varied in accordance 65 with the use to which the stand is to be put.

The end walls 3 and 4 have hinged hasps 7 secured thereto and the side walls 2 and 5 are provided with staples 8 to receive the 70 hasps 7, and pins or other securing devices 9 are adapted to be positioned through the staples after the hasps are located thereon so as to hold the walls in upright position forming a receptacle to receive a churn or 75 other device or receptacle and hold the same against lateral movement during the operation thereof. Recesses 8^a are provided in base 1 to receive the staples 8 and permit the side walls 2 and 5 to lie flat on the base. 80

The side walls 2 and 5 are so hinged that they swing outwardly and downwardly, while the end walls 3 and 4 are so hinged that they swing inwardly and downwardly, so that when said walls are folded or hinged 85 downwardly against the base 1, they will lie relatively flat and occupy but a minimum of space so that the folded stand can be packed or stored in a relatively small space.

The stand may be supported on a table 10 90 or other suitable support and is preferably held against accidental movement by means of removable clamps 11 so that the stand can be located on its supporting table as may be desired and securely held against 95 accidental displacement.

As shown most clearly in Figure 2, it will be noted that when the walls are in an upright position, the end walls 3 and 4 will bear against the ends of the side walls 2 and 100 5 and when the walls are secured in this position by means of the hasps 7, staples 8 and pins 9 and other similar securing means, a rectangular receptacle is formed which will operate to hold a churn or other device 105 against accidental displacement during its operation.

Various slight changes might be made in the general form and arrangement of the parts described without departing from the 110 invention, and hence I do not limit myself to the precise details set forth, but consider

myself at liberty to make such changes and alterations as fairly fall within the spirit and scope of the appended claims.

I claim:

- 5 1. A stand of the character stated, comprising a base, four walls hingedly connected to the base, one pair of parallel walls adapted to swing outwardly and downwardly against the base, the other two of 10 said walls adapted to swing inwardly and downwardly against the base, and means for securing said walls in upright position.
2. A stand of the character stated, com-

prising a base, four walls hingedly connected to the base, one pair of parallel walls 15 adapted to swing outwardly and downwardly against the base, the other two of said walls adapted to swing inwardly and downwardly against the base, hinged hasps on certain of said walls, staples on other of 20 said walls adapted to receive the hasps, and locking devices adapted to be positioned in the staples securing the walls in upright position.

CLARA ALLING KIBBE.
